(57) **CLAIM**

The ornamental design for a wireless bedwetting alarm set, as shown and described.

DESCRIPTION

FIG. 1 is a perspective exploded view of a wireless bedwetting alarm set, showing my new design;

FIG. 2 is a perspective view of the first piece of the wireless bedwetting alarm set shown apart from the other piece for ease of illustration;

FIG. 3 is the second perspective view thereof;

FIG. 4 is the third perspective view thereof;

FIG. 5 is a front elevational view thereof;

FIG. 6 is a rear elevational view thereof;

FIG. 7 is a left elevational view thereof;

FIG. 8 is a right side view thereof;

FIG. 9 is a top side view thereof;

FIG. 10 is a bottom plan view thereof;

FIG. 11 is a partial enlarged view of FIG. 3;

FIG. 12 is a perspective view of the second piece of the wireless bedwetting alarm set shown apart from the other piece for ease of illustration;

FIG. 13 is the second perspective view thereof;

FIG. 14 is the third perspective view thereof;

FIG. 15 is the fourth perspective view thereof;

FIG. 16 is a front elevational view thereof;

FIG. 17 is a rear elevational view thereof;

FIG. 18 is a left elevational view thereof, the right side view being a mirror image of FIG. 18;

FIG. 19 is a top side view thereof;

FIG. 20 is a bottom plan view thereof;

FIG. 21 is a partial enlarged view of FIG. 12;

FIG. 22 is a partial enlarged view of FIG. 12;

FIG. 23 is a partial enlarged view of FIG. 12;

FIG. 24 is a partial enlarged view of FIG. 13; and,

FIG. 25 is a partial enlarged view of FIG. 14.

The broken lines in the figures are for the purposes of illustrating portions of the wireless bedwetting alarm set, which form no part of the claimed design.
